Fig. 8.

A technical drawing of a vertical pipe section. The top part is a vertical line with a hatched rectangular area on its left side. A horizontal line extends from the right side of this hatched area. A dimension line with arrows at both ends spans this hatched area, labeled '66'. Below this, a horizontal line extends further to the right, ending in a small circle with a vertical line through it. A dimension line with arrows at both ends spans this second horizontal section, labeled '71'. To the right of the pipe, there is a handwritten label 'A' above a dimension line with arrows, labeled '76'.

UNITED STATES PATENT OFFICE.

ALEXANDER T. BROWN, OF SYRACUSE, NEW YORK.

TYPE-WRITING MACHINE.

1,098,091.

Specification of Letters Patent. Patented May 26, 1914.

Application filed June 1, 1912. Serial No. 700,939.

To all whom it may concern:

Be it known that I, ALEXANDER T. BROWN, a citizen of the United States, and resident of Syracuse, in the county of Onondaga and State of New York, have invented certain new and useful Improvements in Type-Writing Machines, of which the following is a specification.

One of the principal objects of my invention is to provide an improved chain of connections between the type bars of a front strike typewriter and the keys.

Another object is to provide improved universal bar mechanism for working the carriage escapement.

Another object is to provide a horizontal plate that serves as a sort of top plate for the base part of the machine and which not only protects some of the mechanism from dust and dirt, but also serves as a support for the key levers and sub-levers and other parts of the mechanism.

Other objects will appear hereinafter.

To the above ends, the invention consists in certain features of construction and combinations and arrangements of parts, all of which will be fully set forth herein and particularly pointed out in the claims.

My invention is embodied in the mechanism illustrated in the accompanying drawings, in which—

Figure 1 is a front to rear vertical sectional view of so much of a typewriting machine as is necessary to illustrate the embodiment of my invention therein. Fig. 2 is a view on a larger scale than Fig. 1 and showing the universal bar mechanism and feed dogs and some of the coöperating parts, said parts being shown by full lines in their normal positions and by broken lines in operated positions. Fig. 3 is a view showing parts of Fig. 1 on a larger scale and with some parts broken away or removed and showing also by broken lines the shifted

position of the shiftable mechanism. Fig. 4 is a front elevation in transverse vertical section, with parts broken away. Fig. 5 is a diagrammatic view of the type action and universal bar, and illustrating by full and broken lines various operations of said parts. In this view, the type bar is shown in normal position by full lines and the universal bar is shown in operated position by full lines. Fig. 6 is a fragmentary top plan view, with parts broken away and parts in section, and illustrating the case shift

mechanism. Fig. 7 is a fragmentary side elevation, partly in section, of a part of said case shift mechanism. Fig. 8 is a view similar to Fig. 7 but on a smaller scale and illustrating a modification.

Referring more especially to Fig. 1, the main frame of the machine comprises a base part 1; on which is mounted a sort of base top plate 2 consisting essentially of a horizontal plate or sheet of metal covering part of the rectangular base 1, back of the keyboard. This plate 2 may be secured to the base 1 in any suitable manner, as, for example, by bolts or screws. Front posts 3 and rear posts 4 are mounted on the plate 2 and support a top plate 5 from which rise standards 6, supporting a stationary rail or trackway 7, as shown in Fig. 1, inclined at an angle of about 45° and having race-ways in its upper rear and lower forward edges, for the accommodation of balls or rollers 8 which coöperate with suitable grooved rails 9 formed in a carriage 10 which carries a platen 11.

Front strike type bars 12 are mounted on a segment 13 which, as shown in Fig. 4, consists of a round rod bent, at least through part of its length, in the arc of a circle and having a series of peripheral grooves 14 cut therein and serving as stationary race-ways for anti-friction balls 15 (Fig. 3). Said balls coöperate with rings 16 threaded into the eyes at the heels of the type bars and secured in adjusted position by screws 17 connecting together two lugs 18 projecting from the ring-like hub 19 of each of the type bars. Said ring-like hub is sawed through or split between the two lugs 18 so that the screw 17 tightens the ring or hub about the rings 16 and thus secures said rings in adjusted position. This ball bearing is or may be substantially identical with that shown in the patent to Barr No. 943,643, dated December 21, 1909.

Below the pivotal center of each type bar and projecting somewhat toward the rear from the heel thereof, is a lug or ear 20 to which is pivoted the forward end of a push link 21, the rear end of which is pivoted at 22 to the upper end of a substantially upright sub-lever 23. There is a series of these sub-levers 23 each consisting of a lever of the first order pivoted at 24 in a hanger 25 which is secured by a screw 26 to the rear face of a flange or vertical part 27 of the plate 2. This plate is formed, as may

be best understood by comparing Figs. 3 and 4, with the upstanding flange 27 which is pierced with an arc-shaped series of holes 28, Fig. 4, through which the screws 26 pass. As here shown, the hangers consist of bifurcated blocks of metal which may be formed either by bending up sheet-metal or by sawing through a block of metal a suitable slot for the reception of the sub-lever 23. Near its upper end each of these sub-levers is preferably bent in toward the middle of the machine to get said sub-lever substantially into the plane of the corresponding type bar, as shown in Fig. 4 at 30. This applies solely, or at least more especially, to those sub-levers that are considerably removed from the middle of the machine.

The upper ends of the sub-levers 23 are arranged in an arc substantially corresponding with the arc of the pivots 20 in the heels of the type bars and the lower ends of said sub-levers are preferably arranged in a straight line across the machine. The sub-levers therefore are of varying lengths, those near the middle of the machine being shortest and those near the sides of the machine being longest. In order to main substantially the same leverage throughout the system the hangers 25 are arranged in an arc-shaped series, which will be understood from Fig. 4, which shows the series of holes 28.

The sub-levers 23 are operated at their lower ends by links 31 each pivoted to the sub-lever at 32 and extending from said pivot approximately horizontally toward the rear, being pivoted at 33 to the rear end of a substantially horizontal key lever 34 of the first order, said key lever being pivoted between its ends at 35 and carrying a key 36 at its forward end. The links 31 are comparatively short, as shown, and when one of the keys 36 is depressed to move the pivot point 33 upward to the position shown in broken lines in Fig. 3, the sub-lever 23 and parts connected therewith are operated, throwing the type bar to the printing position. In order to avoid conflict between the key lever and the lower end of the sub-lever, said key lever is formed at its rear end with a substantially upright section 37.

The keys 36 are arranged in four rows as usual as shown in Fig. 1 and in order to give all of them the same leverage relation to the rear ends of their respective key levers 34 the pivots 35 of said key levers are arranged in four banks as will be understood from Fig. 1, the key levers whose keys 36 are in the rear end of the keyboard being pivoted on the rear wire 35; those key levers whose keys are in the second row being pivoted on the second wire 35, and so on. To this end a rib 38 is formed on or secured to the underside of the plate 2 extending across the machine, and said rib has a series of slots

39, Fig. 4, cut therethrough in a front and rear direction, one for each of the key levers 34. As shown in Fig. 3 four holes 40 are drilled through the rib 38 and the four wires 35 are put through said holes. Each of the key levers has an ear 41 formed at a suitable point at its upper edge and said ear lies in one of the slots 39 and is pivoted on one of the wires 35. Other means may of course, if preferred, be provided for inserting the wires 35 than by drilling holes the length of the rib 38. Each of the key levers has a downwardly extending arm 42 to which is connected the rear end of a restoring spring 43. The said springs have their forward ends connected to a row of hooks 44 formed on the edge of a bar 45 secured by screws 46 to the base 1 of the frame.

By providing the four pivots 35, one for each of the transverse rows of keys 36, and by arranging the pivots 24 of the sub-levers 23 in the manner that has been explained, it will be seen that all of the key levers have the same dip and the same leverage on their respective type bars, and that the upper ends of all of the sub-levers 23 move through the same distance when operated.

In the Patent No. 984,744, dated December 21, 1911, I have shown type bar operating mechanism having some of the characteristics of the present mechanism and some of the advantages of the present mechanism, but my present mechanism is an improvement over that shown in the patent. In the patent the key levers are connected by short links with upright sub-levers but said short links extend from the rear ends of the key levers toward the rear of the machine and rock the sub-lever, when a key is depressed, in a direction the opposite to that illustrated in the present case. In the patent the upper ends of the sub-levers are connected by pull links with the type bars, said links being pivoted to said type bars above or inside of the type bar pivots. The result of this is that the upper ends of said sub-levers are arranged in an arc that is of less radius and of less width than the row of type bar pivots and of considerably less width than the system of key levers. This difference in width between the system of key levers and the upper ends of the sub-levers was compensated for in the patented construction by setting said sub-levers on a slope, those near the sides of the machine being inclined inward at their upper ends, with the result that the plane of motion of the key lever did not correspond with that of the sub-lever. In the present instance, by connecting the links 21 with the type bars below or outside the pivots of said type bars, the upper part of the system of sub-levers is about as wide as the system of key levers. The sub-levers are therefore all approximately vertical. I

have also found by experiment that by the particular arrangement shown in the present case, that is to say, with the links 31 extending rearward from the sub-levers and 5 making the links 21 push links instead of pull links, I get an improved action. By the present arrangement I avoid crowding the upper ends of the sub-levers and opportunity is afforded to make all the mechanism 10 more substantial and accessible, and also I find by experience that the present connections from the key to the type bar give a better action in use than those of the patent.

I have provided a very light, simple and 15 effective shifting segment construction. This mechanism includes a frame best shown in Fig. 6 and which consists of two end bars or pieces 47 and a cross bar 48, the latter being made stiff and rigid and 20 being rigidly connected with the former. Preferably this entire frame consists of a single integral piece. The arms 47 are approximately horizontal and are pivoted at their rear ends on pivot screws 50 threaded 25 into lugs 51 projecting from the rear posts 4. The right-hand lug 51 is shown broken away in Fig. 6 in order to disclose other parts of the mechanism. At their forward ends the arms 47 are formed with threaded 30 holes into which are screwed combined pivot and stop screws 52, as perhaps best shown in Fig. 4. Each of these screws has a reduced inner end 53 which projects into a hole 54 in the end of the segment 13, the 35 two holes 54 at the two ends of the segment being in line with each other. The ends of the segment are trued up and abut against the inner surfaces of the arms 47 so that transverse motion of the segment is pre- 40 vented. The construction is such that said segment is pivoted in the frame 47, 48 on the pivots 53. Said frame 47, 48 is adapted to be shifted down and up for upper and 45 lower case writing, its motion in this respect being limited by the elongated heads of the screws 52 coöoperating with stop screws 55 and 56, the screws 55 being above and the screws 56 being beneath the heads of the screws 52. Said screws 55 and 56 50 are threaded through brackets 57 secured to the underside of the top plate 5. Each of these brackets 57 comprises a vertical part and two horizontal projecting ears through which latter the screws 55 and 56 55 are threaded. The vertical part of each of the brackets 57 either contacts with or is very close to the end of the corresponding screw 52 and serves to guide said screw in its up and down motion against motion in 60 a right and left-hand direction.

In order to cause the segment 13 to maintain a vertical position when it is shifted up and down, said segment has pivoted to the middle thereof a guide link 58, which is 65 pivoted at 59, to an ear 60 projecting from

a cross bar 61, which cross bar connects the two rear posts 4. As here shown, said cross bar 61 is integral with said posts, but it can of course be a separate piece secured in position in any suitable way. The forward 70 end of the guide link 58 may be pivoted to the segment 13 in any suitable manner. As here shown (Fig. 6) said guide link is formed at its forward end with the same sort of strap 19 as the heels of the type bars, 75 said strap being split at one point and being provided with a screw 17 like those of the type bars and said link is pivoted to the segment by a ball bearing which occupies the middle one of the grooves 14 of the seg- 80 ment. It will of course be understood that it is not essential that this link be pivoted to the segment by a ball bearing but the form of the segment is such that that is as convenient a way as any to pivot it. 85

A spring 62 is connected at its lower end to the guide link 58 and at its upper end to the top plate 5, and this spring normally holds the segment 13 and the parts associated therewith in their upper positions, as 90 shown, for example, in Fig. 4. Shift key mechanism to be presently described, is provided for pulling the segment down to its lower position for upper case writing.

The type bars 12 near their free ends normally rest against a type rest 63 having a pad 64. In order to shift this type rest up and down with the segment 13 and in a substantially constant relation to said segment, said type rest is supported by arms 65, 100 which at their rear ends are secured to upright bars 66, each at its upper end pivoted at 67 to an ear 68 extending downward from the forward end of one of the arms or bars 47. The bars 66 extend down through 105 holes 70 (Fig. 4) in the plate 2 and just beneath said plate (Fig. 7) each of said bars 66 is pivoted at 71 to the forward end of a guide link 72, which guide link is substantially parallel with the bars 47, being pivoted at its rear end at 73 to a lug 74 depending from the plate 2. These guide links 72, acting on the lower ends of the bars 66, and the arms 47, acting on the upper ends of said bars, maintain said bars in 110 substantially a vertical position, the bars shifting down and up with the type bar segment and causing the type rest 63 to shift correspondingly.

In order to shift the segment downward, a case shift key 75 is provided in the keyboard and mounted on a lever 76, Figs. 3, 4 and 7, which lever at its forward part corresponds in outline with the key levers 34 and at its rear end is pivoted on the same 120 pivot 73 as the guide link 72. Each of the shift key levers 76 is connected with one of the bars 66 by means of a short link or connecting piece 77. The construction is such that when either one of the keys 75 is de- 130

pressed it pulls the segment 13 down to its upper case position, as will be understood from the above description.

Instead of part of the construction above described, the modification shown in Fig. 8 may be employed. According to this modification the guide link 72 is dispensed with and the rear end of the shift key lever 76' is pivoted at 78, and said lever is connected directly at 71' to the lower end of the bar 66. In this construction the rear end of the key lever 76' serves as a guide link for the lower end of the bar 66.

The universal bar mechanism for the carriage escapement, is best shown in Figs. 2, 3 and 4. Each of the posts 4 has a bracket 78 projecting therefrom toward the front of the machine and another bracket or lug 79 projecting therefrom toward the rear. A transverse horizontal rock shaft 80 is pivoted in the forward lugs 78 and a similar rock shaft 81 in the rear lugs 79. The rock shaft 80 has near its ends upright arms 82, which, as shown in Figs. 3 and 4, are pivoted at their upper ends at 83 to brackets 84 projecting from a curved or segmental universal bar 85, lying in the paths of the upper ends of all of the sub-levers 23. Another bracket 86 projects toward the rear of the machine from the universal bar 85 near each end thereof and the rear ends of these brackets or arms 86 are pivoted at 87 to the upper ends of arms 88 projecting upward from the rock shaft 81.

It will be perceived that by the construction shown and described the two rock shafts 80 and 81 are connected together so that they are compelled to rock in unison; and that the frame comprising the universal bar 85 and the brackets 84 and 86, is rigidly mounted and guided so that all parts of the universal bar move in parallel lines and to the same extent.

Any suitable restoring spring may be provided to move the universal bar toward the rear of the machine to its normal position. As here shown, a spring 90 is coiled about the shaft 81 and bears at one end against the stationary framework and at the other against one of the arms 88.

It will of course be understood that the universal bar mechanism shown and described can be connected with any suitable form of carriage escapement by any one of a variety of means. I prefer the construction shown comprising an arm 91 projecting from about the middle of the shaft 81 and having at its upper end dogs 92 co-operating with the teeth 93 of a crown escapement wheel 94 arranged to turn in a horizontal plane, being mounted on a vertical shaft 95, which shaft is journaled in a stationary post 96 of the top plate 5. Near its upper end said shaft 95 has a pinion 97 loose thereon and meshing with a rack 98 on the upper

rail 9 of the carriage 10. The upper end 100 of the shaft 95 is made square, as shown in Fig. 1, and a clutch section or member 101 is slidably mounted on said squared end of the shaft and is formed with clutch teeth 70 that co-operate with corresponding teeth on the upper surface of the pinion 97. The clutch section 101 is formed with a peripheral flange 102 beneath which lies a yoke bar 103, the arms 104 of which are pivoted to the carriage at 105 and are extended forward to form levers of the first order having carriage release keys 106 at their forward ends. This feed rack, clutch and release mechanism are substantially like those shown in my Patent No. 984,744, above referred to. It will be seen that by the present construction the feed dogs are mounted directly on one of the rock shafts constituting a part of the universal bar mechanism. 85

Any suitable means may be provided for limiting the motion of the universal bar under the impulse of the spring 90. In practice I prefer to arrest said universal bar at some such position as is indicated in Fig. 90 2 where it will be seen that the upper ends of the sub-levers make somewhat more than half of their complete stroke before encountering said universal bar.

I prefer to actuate the universal bar 85 by 95 the extreme upper ends of the sub-levers; that is to say, by a point on each of the sub-levers substantially opposite the pivot 22. This particular point has the same extent of motion in all the sub-levers so that by 100 operating the universal bar from this part of each sub-lever said universal bar will be operated the same by all of the sub-levers in the system. Moreover, this part of the sub-levers moves at a uniform and maximum 105 linear velocity. In other words, the universal bar contacts with the sub-lever at the extreme end of the latter at a point where all 110 of the sub-levers move the same distance and at a maximum velocity at the time of contact between the type and platen, so that the escapement let-off can accurately be made very near the termination of the stroke of the type bar. It will be noted that the 115 links 21 are curved upward near their rear ends in order to clear the universal bar under all conditions. These links are also curved downward slightly at their forward ends in order to clear the heels of the type bars when said type bars are in printing 120 position. This will be understood from an inspection of Fig. 5. This curvature of the links also gives said links an elastic or yielding property which improves the 125 quality of the touch on the keys.

The precise arrangement of the universal bar and of the system of sub-levers will be somewhat more clearly appreciated by an inspection of Fig. 5 which shows the universal bar in its forward or operated position and 130

which shows several of the sub-levers of different lengths, the two extreme positions, namely, the normal position and the operated position, of each of said sub-levers being indicated. It will be seen that the sub-levers are so disposed that the vertical plane α through the pivot points 24 is equi-distant in a front and back direction from the normal and the operated position of each of the 10 pivot points 22. The normal positions of all of said points are in a vertical plane a certain distance back of the plane α and the operated positions of all of said points are in another vertical plane at a like distance in front of the plane α .

I have shown a space bar 107 mounted on the forward ends of lever arms 108, each of which at its rear end is pivoted at 109 to a lug 110 depending from the plate 2. Each 20 of the levers 108 is connected by a vertical link 111 with an arm 112 projecting forward from the rock shaft 80. Each of the links 111 passes through a suitable hole 113, Fig. 4, in the plate 2 and each of them at its 25 upper end is bent off so as to pass through a vertical slot 114 in the arm 112. The construction is such that if the space bar 107 be depressed, the universal bar 85 and its connections, including the feed dogs 92, will 30 be operated. But if the universal bar and said connections be operated by one of the sub-levers 23, the slot 114 will move idly with relation to the link 111 and the space bar will not be depressed. Any suitable 35 storing springs may be provided for the levers 108.

The top plate 5 may be curved upward, as shown at 115, to serve as a dust guard and deflector to catch the dust of erasures, and to 40 prevent it from falling over into the type bar bearings. It will be noted that all of the rest of the mechanism is thoroughly protected from falling dust. The top plate 45 itself protects the sub-lever systems, the shifting mechanism and the universal bar mechanism, and the key levers and other parts in the base of the machine are protected by the plate 2, whose dimensions are extended for the purpose. It will be noted 50 that the solid part of this plate comes under the open part of the top plate. The principal opening through the plate 2 is that at 116 where the sub-levers project through it and this is in behind the flange 27, and 55 underneath the solid part of the top plate 5. It will be seen that the system of dust protection in this machine is unusually complete.

It will be noted that the construction is 60 such that both the top plate 5 and the base 1 can be removed, and all of the working parts of the type action remain intact. This is an important feature from the manufacturing point of view as the mechanism can 65 be assembled and adjusted in this manner.

The case shift mechanism, including the shifting segment construction and its connections, is not claimed herein but is claimed in my application, Serial No. 759,879, filed April 9, 1913, which said application is a 70 division of the present application.

Various changes can be made in the details of construction and arrangement without departing from my invention.

What I claim as new and desire to secure 75 by Letters Patent, is:

1. In a typewriting machine, the combination of a series of substantially horizontally disposed key levers, a series of substantially horizontally disposed links pivoted to said key 80 levers at the rear ends thereof and extending longitudinally of said key levers and toward the front of the machine, a series of sub-levers pivoted to said links, a fixed frame to which said sub-levers and said key levers are 85 pivoted, and a series of type bars actuated by said sub-levers.

2. In a typewriting machine, the combination of a series of substantially horizontally disposed key levers of the first order, a series 90 of substantially horizontally disposed links pivoted to the rear ends of said key levers and extending longitudinally thereof toward the front of the machine, a series of 95 standing sub-levers of the first order operated by said links, a series of front strike type bars, and links extending from the upper ends of said sub-levers to said type bars below the pivots of the latter.

3. In a front strike typewriting machine, 100 the combination of a series of substantially horizontally disposed key levers of the first order, a series of links pivoted to the rear ends of said key levers and extending therefrom toward the front of the machine, a 105 series of front strike type bars, a series of 110 standing sub-levers of the first order arranged in rear of said series of type bars and connected at their lower ends to said links, and a series of push links connecting the upper ends of said sub-levers with said type bars.

4. In a front strike typewriting machine, 115 the combination of a series of keys, a series of front strike type bars, a series of 120 standing sub-levers operated by said keys and having their upper ends arranged in an arc, substantially horizontally arranged push links pivoted to said type bars and to the upper ends of said sub-levers, and a curved universal bar arranged between said type bars and said upper ends of said sub-levers, said push links being suitably curved to clear said universal bar.

5. In a typewriting machine, the combination of a frame base, a horizontal plate above said base, a top plate supported above said horizontal plate, key levers mounted beneath said horizontal plate, front strike 125 type bars above said horizontal plate and 130

below said top plate, and connections from said key levers to said type bars, said connections being in rear of said type bars and said horizontal plate having near the rear of 5 the machine an opening for said connections, and said top plate standing over said opening.

6. In a typewriting machine, the combination of a horizontal frame plate in the 10 lower part of the machine, key levers pivoted to the under side of said plate, sub-levers pivoted to said plate above said key levers, means operatively connecting said sub-levers with said key levers, and type 15 bars operated by said sub-levers, said plate being extended rearwardly beyond the sub-levers and provided with an opening for the lower ends of said sub-levers.

7. In a typewriting machine, the combination of a horizontal frame plate in the 20 lower part of the machine, key levers pivoted to the under side of said plate, an upturned flange in said plate, sub-levers connected with said key levers and pivoted to 25 said flange, and type bars operated by said sub-levers, said plate being extended rearwardly beyond the sub-levers and provided with an opening for the lower ends of said sub-levers.

8. In a typewriting machine, the combination of a top plate, a horizontal frame plate in the lower part of the machine and extending from the front of the machine rearwardly under the top plate, said horizontal 35 frame plate having between its ends an integral vertical flange, key levers pivoted on the under side of said horizontal frame plate, sub-levers pivoted on said vertical flange, said sub-levers extending through 40 an opening in the rear portion of the horizontal frame plate, and connections between the lower ends of said sub-levers and the rear ends of said key levers.

9. In a typewriting machine, the combination of a frame including a base part and 45 upright posts, printing keys, printing instrumentalities, connections from said printing keys to said printing instrumentalities including a series of levers, a curved uni-

versal bar operated by said levers, two transverse rock shafts supported by two of said posts and having arms that support said universal bar, and devices operated by said universal bar.

10. In a typewriting machine, the combination with key levers, up-standing sub-levers operated by said key levers, and front-strike type bars operated by said sub-levers, of a universal bar curved in a vertical plane, and arranged to be operated by said sub-levers, two parallel rock shafts, one in front of the other and each having two upright arms thereon, and arms projecting horizontally from said universal bar, said horizontal arms pivoted to said upright arms 65 whereby said universal bar is guided for a bodily motion of translation in a substantially horizontal direction.

11. In a typewriting machine, the combination of a frame including a base part and upright posts, printing keys, printing instrumentalities, connections from said printing keys to said printing instrumentalities including a series of levers, a curved universal bar operated by said levers, two transverse rock shafts supported by two of said posts and having arms that support said universal bar, devices operated by said universal bar, and a space key operatively connected with said universal bar.

12. In a typewriting machine, the combination of a series of type bars, a series of upstanding sub-levers connected with said type bars, key levers of the first order having their rear ends in the rear of the lower 85 ends of said sub-levers, and links connecting the rear ends of said key levers with the lower ends of said sub-levers, the rear part of each key lever having a recessed portion to allow of the upward motion of the key 90 lever without collision with the sub-lever.

Signed at Syracuse, in the county of Onondaga, and State of New York, this 29th day of May A.D. 1912.

ALEXANDER T. BROWN.
